UNITED STATES PATENT OFFICE.

GOTTWALT SIEBER, OF PLAUE, GERMANY.

METHOD OF SECURING THE END WINDINGS OF BOBBINS.

1,411,460.

Specification of Letters Patent.

Patented Apr. 4, 1922.

No Drawing.

Application filed September 10, 1921. Serial No. 499,856.

To all whom it may concern:
Be it known that I, GOTTWALT SIEBER, a citizen of the Republic of Saxony, residing at Plauen, in Saxony, Germany, have invented certain new and useful Improvements in Methods of Securing the End Windings of Bobbins, of which the following is a specification.

This invention relates to method of securing the end-windings of bobbins wound on spooling machines. The bobbins placed in the shuttles of embroidering machines formerly were produced in bobbin winding machines by winding a thread on the rapidly rotating spool-bar, thereby moving the thread to and fro in the axial direction of the latter. This winding operation had to be continued till the necessary diameter and the bulged form of the bobbin was attained, and then the latter was shifted laterally as far as space was required for the formation of a new bobbin.

Thereby the securance of the end windings was of very great importance since the bobbin had to be prevented from unwinding when in use. For this purpose the end-windings were placed across the bobbin in the form of several thread-layers and the thread-end which remained between the ready and half-ready bobbin sometimes was twined or twisted with the beginning of the bobbin, or a loop was formed of any thread-layer of the bobbin's cross-winding and twisted or joined with the thread-end.

All these methods are, however, very disadvantageous as the bobbins in spite of all caution unwound very easily in operation when being packed and placed in the shuttles so that a considerable loss of thread ensued. In addition thereto, it must be considered that a lot of yarn was squandered by the necessity of placing the end-thread in form of several windings around the bobbin because the yarn wound across the bobbin as is well known cannot be used for the embroidering operation. Now since about 1000 shuttles are simultaneously in operation in great embroidering machines of modern construction the loss in yarn therefore is very considerable.

In the present method all these drawbacks completely are done away with, since a feature of the present invention consists in that the end-windings of the bobbin formed of the last thread and laid across the

bobbin are completely omitted. Instead thereof a number of windings are formed of a special thread and also placed across the bobbin.

In operation the present new method is applied as follows. As soon as the bobbin is wound to the desired thickness a thread arising from a special source of thread is placed several times around or across the body of the bobbin. For this purpose the bobbin on the bobbin-bar is shifted for a whole bobbin length in longitudinal direction and thus conducted to the operation of winding by means of a special thread.

In the specification the thread serving for the winding or spooling of the bobbin-body is called bobbin-thread while the thread destined to prevent the end-windings of the bobbin from unwinding is named binding-thread. When the bobbin wound on the spool-bar of a bobbin-winding machine has attained the diameter desired the finished bobbin as stated above, by means of a suitable device is removed or shifted so far as to make room for the production of a new bobbin. After this the binding-thread by means of a special device, for instance a thread-layer, rotating about the thread-guide, is laid several times around the bobbin, the beginning of the bobbin-thread thereby being advantageously held fast by means of a clamping device arranged outside of the bobbin diameter.

After the binding-thread is placed several times around the bobbin this thread is introduced into the clamping device or any other device and fixed there. Thus both the beginning and the end of the binding-thread are held fast, and by means of any suitable device these two threads are twisted, and the bobbin is finished.

The advantages of the invention are various. Firstly the drawback is avoided of rendering considerable quantities of yarn useless, since by means of this invention the embroidery thread may be completely used up. Another advantage consists in that a different material can be applied for the binding thread than for the bobbin, especially when the bobbin-body consists of very expensive thread. On the other hand, material of little value may be applied for the winding of the binding-thread; and the sort of yarn to be used or used for the bobbin can be marked by means of a coloured bind-

2
ing-thread so that errors formerly arising in embroidering with thread of different thickness thus are completely excluded.

Having now fully described my invention
5 I declare that what I claim is:—

1. Method for securing the end-windings of bobbins in shuttle embroidering machines, consisting in that after the completion of the bobbin-winding a binding-thread, from 10 a special source of thread, is placed in several windings around the bobbin-body and then the beginning and end of the binding-thread are twisted, substantially as described.
- 15 2. Method for securing the end-windings of bobbins in shuttle embroidering machines, consisting in that after the completion of the bobbin-winding a binding-thread, from a special source of thread, is placed in several windings around the bobbin-body and the beginning of the binding-thread being seized by a clamping-device before the commencement of its winding on the bobbin, till 20 it is twisted with the end of the binding-thread, substantially as described.
- 25 3. Method for securing the end-windings of bobbins in shuttle embroidering machines, consisting in that after the completion of

the bobbin-winding a coloured binding-thread from a special source of thread is placed in several windings around the bobbin-body and the beginning of the binding-thread being seized by a clamping-device before the commencement of its winding on the bobbin till it is twisted with the end of the binding-thread, substantially as de- 30 35 scribed.

4. Method for securing the end-windings of bobbins in shuttle embroidering machines, consisting in that after the completion of the bobbin-winding a binding-thread of 40 minor material than the bobbin-thread from a special source of thread is placed in several windings around the bobbin-body and the beginning of the binding-thread being seized by a clamping-device before the commencement of its winding on the bobbin, till it is twisted with the end of the binding-thread, substantially as described. 45

In testimony whereof I affix my signature in presence of two witnesses.

GOTTWALT SIEBER.
